WINDOW OPERATING DEVICE

Filed Dec. 6, 1928

Inventor
Charles Hilmer

By Nelson, Mann & Co., Atty.

UNITED STATES PATENT OFFICE

CHARLES HILMER, OF CHICAGO, ILLINOIS

WINDOW-OPERATING DEVICE

Application filed December 6, 1928. Serial No. 324,077.

This invention relates to closure operating devices and more particularly to window operating devices.

The principal object of the invention is the provision of new and improved devices for raising and lowering the upper section or sash of a window.

Another object of the invention is the provision of a new and improved window operating device that is provided with novel means for attaching it to the window sash whereby the same will be securely and permanently secured thereto.

A still further object of the invention is the provision of a new and improved window operating device that is simple in construction, cheap to manufacture, easily attached in position on the window, that is light in weight, efficient in use and ornamental in appearance.

Other and further objects and advantages of the invention will appear from the following description taken in connection with the accompanying drawings, in which

Fig. 1 is a vertical section of a portion of a window showing the invention in position thereon;

Fig. 2 is a front elevation of the operating device;

Fig. 3 is a front elevation of the lower portion of the device, showing the same in operative position, with parts broken away;

Fig. 4 is a front elevation of a portion of a window showing a modified form of construction in position thereon;

Fig. 5 is a vertical section of a portion of a sash showing a modified form of construction thereon;

Fig. 6 is a section on line 6—6 of Fig. 5;

Fig. 7 shows a still further modified form of means for attaching the operating device to the sash; and

Fig. 8 shows a further modified form of attaching means for the operating device.

Referring now to the drawings, the reference character 10 designates generally a window comprising an upper glazed sash 11 and a lower glazed sash 12. Each sash is provided with the stiles 13 and upper and lower rails 14 and 15, respectively, see Fig. 1, as is

usual in such constructions. Since the window is of the usual or any well known construction, it is not thought necessary to further illustrate or describe the same.

The meeting rails 14 and 15 are provided with the usual interlocking or latch member 16 and keeper 17 for locking the two sashes together to prevent the window from being opened from above or below. The latch member 16 is provided with the operating handle 18 for rotating the same as is usual in such constructions.

The preferred form of window operating device is shown in Figs. 1 and 2 and comprises a single length of wire or rod doubled on itself to form a loop 19 of any suitable construction which constitutes a handle 21 for operating the device. The two end portions of the wires or rods may be and preferably are connected together as by twisting to form the body portion 22. The ends of the wires are each given a right angle bend as at 23 and 24 and are then return bent to form loops or eyes 25 and 26 through which fastening means such as the screws 27 are adapted to pass for securing said loops to the under side of the upper rail 14, as clearly shown in Fig. 1 of the drawing.

In order to firmly secure the device to the upper rail 14 the extreme ends of the wires are bent at right angles to the loops 25 and 26 and formed into loops or eyes 270 and 28 which are adapted to be attached to the side of the upper rail 14 as by means of the screws 29.

By providing the attaching eyes at right angles to each other the device will be rigidly and firmly attached to the rail with little likelihood of its becoming detached.

It is desirable that the device be so attached that there will be no tendency for the window to twist or bind on raising, or lowering the same, but that it will operate evenly and smoothly without undue friction during the raising and lowering operation.

This function is accomplished in the present invention by the divergent end portions of the device. The end portions being separated at their upper ends are attached at widely separated points at each side of the

center line of the window, consequently a pull or push on the handle 21 will cause both sides of the window to move together with a minimum amount of binding or friction.

5 The body portion 22 is offset sufficient to provide ample clearance between the handle and the lower sash. Suitable means are provided for limiting the downward movement of the upper sash relative to the lower. In 10 the form of construction selected to illustrate one embodiment of the invention, a loop 31 is slidably mounted on one of the wires between the twisted body portion 22 and the handle portion 21, the wires being separated at this 15 point sufficiently to receive said loop. The loop is adapted to engage the handle 18 of the window fastener for limiting the downward movement of the upper sash. By means of this arrangement the two sashes will be 20 limited in their overlapping relation, whereby the upper sash may not be lowered nor the lower sash raised beyond a predetermined amount, thereby preventing unauthorized entry of persons through the window opening.

25 In Fig. 4 is shown a modified form of construction in which the window operating device is in the form of a bail 32 having its upper end portion bent inwardly as at 33 and then laterally as at 34 and 35 for engaging 30 openings in the outstanding flanges of plates 36, 37 as clearly indicated in said figure.

In Figs. 5 and 6 is shown a further modified form of construction in which the window operating device comprises a single wire 38 or rod 38 having its upper end portion bent laterally as at 39.

40 The end of the wire or rod 38 is flattened and tapered as shown at 41 and 42. When a device is to be attached to the sash a hole 43 having the diameter of the wire is bored or drilled into the sash and the flattened end 41 is driven into the sash. The laterally extending portions of the flattened end will cut a slot at each side of the hole, but these slots 45 will close up more or less behind the cutting edges of the flattened portion.

50 A ferrule or thimble 44 surrounding the bent portion 39 of the rod 38 and having the return bent flange 45 is adapted to be driven into the hole for fastening the rod in position therein, as indicated in Figs. 5 and 6 of the drawing.

55 In Fig. 7 is shown a modified form of means for attaching the operating device to the upper rail of the upper sash. In this form of construction, a plate 46 rigidly attached to the rail 47 as by means of the screws 48 is provided with a central offset portion 49 through which the bent portion 49 of the operating 60 rod 51 extends. The rod may be provided with a shoulder 52 for engaging the plate 48 at one side thereof and the end is riveted or headed over as at 53 for rigidly securing the operating rod in position.

65 In this form of construction, the operating

member comprises a single rod but it is understood that this means of attachment may be employed with a plurality of rods, or a rod doubled on itself as shown in Figs. 1 and 2.

70 In Fig. 8 is shown a slightly modified form of means for attaching the operating member to the window. In this form of construction, a bracket 54 similar to the brackets 36 and 37, see Fig. 4, and attached in the same manner, is provided which extends laterally from the window rail 55 a sufficient distance 75 to enable the handle member to clear the lower sash, as in Fig. 1. The bracket is provided adjacent its outer end with an opening 57 in which is pivoted the upper bent end of the operating rod 56 in a manner similar to that 80 shown in Fig. 4.

In all forms of the device the handle and body portion of the device are offset a sufficient distance to clear the lower sash in 85 lowering the upper sash.

90 It is thought from the foregoing taken in connection with the accompanying drawings that the construction and operation of my device will be apparent to those skilled in the art, and that changes in size, shape, proportion and details of construction may be made without departing from the spirit and scope 95 of the appended claims.

I claim as my invention:

1. In combination, a window comprising 100 an upper and lower sash, a fastening device on the adjacent rails of said sashes for locking said sashes together, an operating device, means for attaching said device to the upper rail of said upper sash, said device extending outwardly and downwardly, a handle on the lower end of said device, and means on said device for engaging said fastening device for holding said upper sash in adjusted position. 105

2. A closure operating device comprising a single length of wire doubled on itself to form a handle member, a body portion and an attaching member, said attaching member having vertical and horizontal attaching lips. 110

3. A window operating device comprising a single length of wire doubled on itself to form a loop-shaped handle and twisted to form a body portion, the free ends of said wire each being bent to form two attaching eyes 115 arranged at right angles to each other.

4. A window operating device comprising a single length of wire doubled on itself to form a loop-shaped handle and twisted to form a body portion adjacent to said handle, the free ends of said wire extending divergently from said body portion, and each of said ends being bent to form attaching eyes for attaching said device to a window sash. 120

125 In testimony whereof I affix my signature.
CHARLES HILMER.
